UNITED STATES PATENT OFFICE.

MICHAEL F. BROGAN, OF LAWRENCE, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING UPON SHOE SOLES.

Application filed November 4, 1920. Serial No. 421,750.

This invention relates to machines for operating upon soles and more particularly to a machine for moulding or breaking down the margins of soles for turn shoes. The 5 method of shoemaking herein disclosed has been described and claimed in my divisional application Serial No. 669,427, filed October 18, 1923, and is therefore not claimed here.

Heretofore it has been the practice to 10 mould or break down the margins of turn soles, for the purpose of facilitating the lasting and upper-sewing operations, before the soles have been secured to the lasts, by means of a machine which feeds the margin of the 15 sole progressively past the moulding tools such, for example, as the moulding machine disclosed in Letters Patent of the United States, No. 1,110,637, granted September 15, 1914, on application of William C. Meyer. 20 After being moulded the soles are usually stacked one on top of another and it has been found that owing to the necessary delay before the assembling operation is performed the moulded margins of the soles have a 25 tendency to return to their normal flat condition. Should this flattening of the margin occur there is interference with the action of the needle during the upper sewing operation resulting in a crippled shoe.

30 An object of the present invention is to provide an efficient and reliable machine for moulding the margins of turn soles in such manner, and in such sequence in the series 35 of shoemaking operations, as will preserve the marginal break until after the upper sewing operation has been performed.

With this object in view the present invention, in one important aspect, provides 40 a tool for engaging the flesh side of a sole while on the last, so shaped as to mould or break down the marginal or feather portion 45 of the sole. In the preferred embodiment of the invention the tool is arranged to vibrate vertically and, in one form, is adapted to engage the sole margin throughout a comparatively small portion only of its length at one time as the last having the sole secured thereto is pressed upwardly by the operator against the lower or acting portion of the 50 tool. This form of tool, which is particularly well adapted for use along the sides of the sole, thus operates to break down the margin of the sole progressively, the sole being drawn across the tool by the operator. In 55 order to facilitate the manipulation of the

sole by the operator this tool is preferably provided with a pair of oppositely disposed moulding faces, said faces being directed outwardly toward the sides of the machine and thus adapted to engage the margin at 60 each edge of the sole in turn by merely shifting the sole laterally across the tool. An abutment, in the nature of a sole support, is provided at either side of the tool to assist the operator in holding the sole in position 65 for the proper operation of the tool thereon and to enable it to be supported to receive the blows of the tool.

A further feature of the invention contemplates the provision of a tool shaped for 70 moulding at one operation the entire marginal portion of the sole about the tip of the toe. The provision of this tool avoids the necessity of turning the sole at the toe, speeds up the operation and provides for 75 more accurate toe moulding. In the preferred embodiment of the invention the toe moulding tool is vibratory and conveniently a single vibratory tool-carrier is employed upon which two moulding tools having the different characteristics described 80 are mounted.

The invention further consists in the features of construction and combinations 85 of parts hereinafter described and particularly pointed out in the appended claims, the advantages of which will be apparent to those skilled in the art.

The various features of the invention will be readily understood from a description of the preferred embodiment thereof illustrated in the accompanying drawings, in which the invention has been shown for purposes of description as applied to a nurling machine of the type disclosed in Letters Patent of the United States No. 768,560, granted August 23, 1904, upon an application of Louis A. Casgrain.

In the drawings, Figure 1 is a view partially in side elevation and partially in section, of the upper portion of a machine of the type above specified, showing the application of the present invention thereto; Fig. 2 is a view, in front elevation and on an enlarged scale, of the operating instrumentalities of the machine, showing a last having a turn sole secured thereto in position to be operated upon; Fig. 3 is an inverted plan view of the moulding tool for operating upon the toe of the sole; and Fig. 4 is 105 110

a detail plan view of the work support or guide.

In the embodiment of the invention illustrated in the drawings, the frame 10 of the machine, the face plate 12, the tool-carrier 14, and the rotary hammer 16, mounted on the driving shaft 18 for imparting a rapid succession of percussive blows to the tool carrier, all may be, and preferably are, of the same design as like parts in the patent to Casgrain hereinbefore referred to. The driving shaft 18 is provided with the usual fast and loose pulleys, (not shown) for controlling its rotation. In accordance with the present invention, the work is to be manually supported and fed as it is presented to the operating instrumentalities of the machine, and consequently the present machine is not provided with a work-table or with a work-feeding device as in the machine of said patent to Casgrain.

The moulding tool which operates upon the opposite lateral edge portions of the sole is indicated at 24, in Figs. 1 and 2. The moulding tool 24 comprises a rectangular block which is rigidly secured to the tool carrier 14 to vibrate rapidly therewith as the latter is acted upon by the rotary hammer 16. To this end a hole 26 (Fig. 1) is bored transversely through the moulding tool 24 to receive a cylindrical stud 28, conveniently formed by machining a tool-sustaining projection with which the tool-carrier 14 of said nurling machine is provided. The tool 24 is located, with its length vertically disposed, by means of a shoulder 30 (Fig. 1) which is formed on the tool-carrier to engage the upper end of the tool. The tool 24 is rigidly secured to the tool-carrier by means of a binding screw 32 that is threaded into an axial recess in the stud 28, the head of the screw 32 bearing against a washer 34 which, in turn, bears against the front face of the tool. The moulding of the lateral margins of the sole is performed by one or more moulding faces at the lower end of the moulding tool 24, such as are indicated at 38 and 40 in Fig. 2. These moulding faces are so proportioned as to engage the margin of the sole throughout only a comparatively small portion of its length at one time and are shaped to impart the desired amount of transverse curvature thereto. In operation the sole is slowly drawn across the moulding face of the rapidly vibrating moulding tool 24, the operator preferably first presenting to said face the rearmost point in that portion of the lateral margin which is to be moulded and then slowly drawing the last forwardly to progressively mould the sole margin until the tool reaches a point near the toe of the sole. The breaking down may be aided by rubbing the sole back and forth under the tool.

To avoid the necessity of turning the last end for end, after one lateral edge of the sole has been moulded, in order to bring the opposite lateral edge thereof into the field of operation of the moulding tool, it is preferred to provide a pair of oppositely disposed moulding faces upon the tool 24. To this end the moulding face 38 is formed at the left side of the moulding tool and arranged to operate upon the margin of the sole at one side and a similar moulding face 40 is formed at the right side of the moulding tool and arranged to operate upon the margin of the sole at the other side. With this construction after one lateral edge of the sole has been operated upon by one of the moulding faces, the operator may readily present the opposite lateral edge of the sole to the other moulding face by merely shifting the sole laterally beneath the tool. Thus the operator is relieved of the extra labor involved in the turning of the last, and considerable time is saved at each sole moulding operation.

To assist in locating the sole relatively to the moulding tool 24, and to maintain the sole in position to receive the blows delivered by the moulding tool and at the proper transverse angle for the most advantageous operation thereof, an abutment is provided against which the upper or exposed face of the sole may be pressed. The abutment, or sole support, herein also termed a work guide, is carried at the lower end of a vertical post 44 which is received in a socket formed in a block 46, the latter corresponding to a similar block in the machine of the patent to Casgrain hereinbefore referred to. The post 44 is rigidly but adjustably secured in the socket of the block 46 by means of a suitable clamping screw 47, this construction permitting such vertical adjustment of the support relatively to the moulding tool 24 as may be required in order to secure the best results from the action of said tool. As best shown in Fig. 4, the sole support comprises a yoke-shaped member having parallel work-engaging arms 42 which project horizontally on opposite sides of the moulding tool 24. The arms 42 are adapted, by engagement with the upper face of the sole as the latter is pressed upwardly against said arms by the operative during the moulding operation, to locate the sole vertically and position it at the proper transverse angle for the moulding operation. The arms 42 are curved longitudinally, as shown in Fig. 1, to permit them to engage the face of the sole margin at the shank of a sole, if it is desired to mould said portion of the margin. The lower face of each arm 42 is disposed transversely at a slight angle to the horizontal to position the sole transversely at the angle illustrated in Fig. 2, since it has been found that the margin may

be more readily moulded into the required transverse curvature when the sole is thus supported. The width of each arm 42 is such as to provide a firm support for enabling the operative to hold the sole at the proper height and angle to receive the blows delivered by the tool. To reduce friction between the arms 42 and the sole as the latter is drawn across said arms, and also to avoid the closing of the channel in the sole by the arms, the lower face of each arm is cut away, as indicated at 48 in Fig. 2, so that it will engage the sole upon opposite sides of the channel but will not rub against the channel flap.

It is difficult, especially when operating upon soles having pointed toes, for the operative to swing the last to effect the moulding of the margin at the tip of the toe without injuring the sole. In accordance with the contemplated use of the machine herein shown, conveniently before or after the opposite marginal portions of the sole have been moulded by drawing said portions successively across the moulding faces on the tool 24, the marginal portion about the tip of the toe is presented to a second moulding tool 50 which is secured to the upper portion of the moulding tool 24 and vibrates with the latter. The tool 50 is of substantial V-shape as shown in Fig. 3, to conform to the shape of the toe, and is provided with a cylindrical projection 52 which is received in a hole bored transversely through the upper portion of the tool 24, and securely fastened therein by means of a suitable binding stud 54 (Figs. 1 and 2). The forks forming the sides of the tool 50 project forwardly from the tool 24 in a substantially horizontal plane, and the lower or acting side is curved transversely to form a continuous concave moulding face similar to the faces 38 and 40 of the tool 24. The particular cross-sections of the lower or acting faces of both of the moulding tools will vary since the tools are shaped to conform to the requirements of the manufacturer.

Before or after both lateral edges of the sole have been operated upon by the moulding tool 24, the toe of the sole is presented to the rapidly vibrating toe moulding tool 50, the operator pressing upwardly on the last to hold the sole against the under moulding face of the tool, and is held in contact therewith until the projecting margin about the tip of the toe is moulded or broken down over the edge of the last to the required extent. It will be observed that the moulding tool 50 is located in front of and above the plane of the abutment 42 to avoid possibility of interference by the latter with the moulding operation at the toe.

When, in accordance with the usual custom, the margin of a turn sole is moulded before the sole is secured to the last, there

is necessarily considerable delay and additional handling of the sole before the upper sewing operation. Largely on account of this delay and partly on account of the way in which the soles are handled after being moulded and before being secured to the last in the assembling operation, there is a marked tendency for the moulded margin to return to its normal flat condition, as hereinbefore set forth. If, however, the sole is secured to the last before its margin is moulded, no such tendency is present since the upper may be immediately assembled on the last with the sole and lasted, making the shoe at once ready for the performance of the upper sewing operation.

It will be recognized by those skilled in the art that the moulding of the margin of a turn sole after the sole has been secured to the last is accomplished rapidly and effectively by means of the above described machine.

In turn shoemaking the first last is reduced in size so that its bottom edge is opposite the shoulder on the flesh side of the sole which forms the striking shoulder for the needle. Thus the last edge is properly located to act as the anvil about which the angle of the break should be made in the margin moulding operation. As a result, the moulded margin always is correctly located or, vice versa, the last always is correctly positioned relatively to the sole. The immediate lasting of the upper preserves the mould in the margin which is made by the machine thereby insuring a properly shaped shoe and a well formed upper.

While it is preferred to employ the specific construction and arrangement of parts shown and described, it will be understood that this construction and arrangement is not essential except so far as specified in the claims and may be changed or modified without departing from the spirit and true scope of the invention.

What is claimed as new is:—

1. A machine for operating upon channeled soles having, in combination, a moulding tool for engaging the face of a sole adjacent its margin, and means for rapidly vibrating said tool in a direction generally perpendicular to the plane of the sole, the tool being shaped to bend out of the path of a sewing needle passing through the channel the marginal portion of the sole as the latter is presented to the tool.

2. A machine for operating upon soles having, in combination, a tool holder, a tool mounted on said holder and shaped for breaking down the marginal portions of a sole, and means for imparting to the holder a succession of rapid blows in a direction generally perpendicular to the plane of the sole.

3. A machine for moulding the margin of a turn sole after assembly of the sole on a

- last having, in combination, a tool shaped to break down the margin of the sole over the edge of the last, and means for imparting to said tool rapidly repeated operative movements in a direction heightwise of the last.
4. A machine for moulding the margin of a turn sole after assembly of the sole on a last having, in combination, a movable tool support, a tool carried by the support shaped to break down the margin of the sole over the edge of the last, and means acting on said support to impart to said tool rapidly repeated operative movements in a direction heightwise of the last.
5. A machine for moulding the margin of a turn sole over the edge of a last after assembly of the sole on the last having, in combination, a tool having an acting portion shaped to fit the desired angle of a properly broken down margin, means for imparting to the tool rapid percussional impulses, and means for supporting the sole to receive the blows delivered by said tool.
6. A machine for moulding the margin of a turn sole after assembly of the sole on a last having in combination, a tool having an acting face for engaging the feather of the sole where it projects beyond the last and bending said feather over the edge of the last, means to impart rapid vibration to said tool, and a member beside the tool against which the face of the sole may be pressed by the operative.
7. A machine for operating upon soles having, in combination, a tool for engaging the marginal portion of a sole throughout a small portion only of its length at one time and shaped to break down the marginal portion of the sole, and means for rapidly vibrating the tool in a direction generally perpendicular to the plane of the sole to cause it to break down the marginal portion of the sole in progressive stages as said portion is brought within the field of operation of the tool.
8. A machine for operating upon soles having, in combination, a tool provided with oppositely disposed faces severally shaped to mould respectively the opposite marginal portions of a sole as they are separately presented to said faces, and means to impart rapid vibrations to said tool in a direction generally perpendicular to the sole.
9. A machine for operating upon soles having, in combination, a tool having a moulding face adapted to engage a portion of the face of a sole adjacent its lateral margin, a second tool having a moulding face shaped to conform to the angle of the toe for engaging the marginal portion of the sole about the tip of the toe, and means for actuating said tools to mould said portions of the sole as they are separately presented to the tools.
10. A machine for operating upon soles having, in combination, a tool carrier, a tool mounted on said carrier and adapted to engage the face of a sole adjacent its lateral edges, a second tool mounted on said carrier for engaging the marginal portion of the sole adjacent the tip of the toe, and means for rapidly vibrating said tool carrier to cause said tools to mould the margin of the sole as it is separately presented thereto.
11. A machine for operating upon turn soles having, in combination, a device provided with a moulding face for engaging the lateral margin of a sole throughout a comparatively small portion of its length at one time, and a second moulding face for engaging the margin of the sole simultaneously at the tip of the toe and at opposite sides of the sole adjacent said tip, and means for rapidly vibrating said device to cause it to progressively mould the lateral margin of the sole as said margin is drawn across the first moulding face, and to mould the entire sole margin about the tip of the toe as said toe portion is presented to the second moulding face.
12. A machine for moulding the margins of soles having, in combination, a tool for simultaneously moulding the entire toe portion of the margin at the tip of the toe and at opposite sides of the sole adjacent said tip, and means to impart rapid vibrations to said tool.
13. A machine for moulding the margin of a turn sole after assembly of the sole on a last having, in combination, a moulding tool of substantial V-shape having an acting portion shaped to break down the margin projecting about the toe of the last, and means for causing said tool to perform its moulding operation.
14. A machine for moulding the margins of soles having, in combination, a vibratory moulding tool shaped to break down the sole margin over the edge of a last, a work guide for locating the sole relatively to said tool for the margin moulding operation, and means for rapidly vibrating the tool to break down said margin.
15. A machine for moulding the margins of soles having, in combination, a vibratory moulding tool, a work guide for engaging the face of the sole and positioning it at an angle with relation to the line of vibration of said tool, and means for actuating said tool to cause it to perform its moulding operation.
16. A machine for moulding the margins of soles having, in combination, a moulding tool having oppositely disposed faces for engaging the opposite lateral margins of a sole as said portions are separately presented thereto, a work guide adjacent each of said faces for locating the work relatively there-

to for the margin moulding operation, and means for actuating said tool to mould the margin of the sole.

17. A machine for moulding the margins of channeled soles having, in combination, a moulding tool, a work guide for positioning the sole relatively to the moulding tool for the margin moulding operation and adapted to engage the face of the sole on opposite sides of the channel, said guide being recessed to prevent engagement with the free edge of the channel flap, and means for actuating the tool to cause it to perform its moulding operation.

18. A machine for operating upon turn soles previously secured to the last having, in combination, a tool provided with oppositely disposed faces for moulding the lateral margins of the sole projecting at opposite sides of the last as said margins are separately presented to said faces, a work guide for positioning the sole relatively to said tool comprising a member forked to

straddle said tool and adapted to be engaged by the face of the sole as said margins are presented to one or the other faces of said tool, and means for actuating said tool to cause it to perform its moulding operation.

19. A machine for operating upon turn soles previously secured to the last having, in combination, a vibratory device provided with a moulding face at its lower end for progressively moulding the lateral margin of the sole projecting at the side of the last as said margin is drawn across said moulding face, a work guide adjacent said face to position the margin thereof with respect to said moulding face, a second moulding face on said device above said work guide adapted to simultaneously engage the margin of the sole at the tip of the toe and at opposite sides of the sole adjacent said tip, and means for actuating said device to cause it to perform its moulding operations on said sole margin.

MICHAEL F. BROGAN.
